UNITED STATES PATENT OFFICE.

WILLIAM E. HILLSON, OF CRANDON, WISCONSIN.

WAVE-MOTOR.

No. 882,883.

Specification of Letters Patent. Patented March 24, 1908.

Application filed August 8, 1907. Serial No. 387,686.

To all whom it may concern:

Be it known that I, WILLIAM E. HILLSON, a citizen of the United States, residing at Crandon, in the county of Forest and State 5 of Wisconsin, have invented a certain new and useful Wave-Motor, of which the following is a specification, reference being had therein to the accompanying drawing.

This invention relates to wave motors or 10 mechanical motors in which the power generated is derived from the rising and falling action of waves, the object of the invention being to provide a simple, inexpensive and efficient device of the character referred to 15 which may be anchored or held in any suitable way at a point where it will be subjected to the action of the waves, and which, in its construction embodies a sectional float the sections of which have a relative move- 20 ment to each other, such sectional float having combined therewith simple mechanism whereby the motion of the sections of the float is converted into rotary motion, the driven member being preferably 25 in the form of a shaft from which the power may be taken off and delivered to a suitable point and utilized.

With the above and other objects in view the nature of which will more fully appear 30 as the description proceeds, the invention consists in the novel construction, combination and arrangement herein fully described, illustrated and claimed.

In the accompanying drawings:—Figure 35 1 is a side elevation of the wave motor complete. Fig. 2 is an enlarged detail side elevation, showing the mechanism for converting the movement of the float sections into rotary motion. Fig. 3 is an enlarged 40 side elevation of the converting mechanism, and Fig. 4 is a sectional end view of said mechanism.

The wave motor contemplated in this invention comprises a float made up of a plurality of sections 1 and 2, each of which is 45 water tight or buoyant, and these sections are connected together by a hinge or pivot joint so that they may alternately and independently rise and fall at their outer ends, 50 while the inner jointed ends thereof rise and fall together, as indicated in Fig. 1, wherein the jointed connection or pivot is shown at 3. If desired one of the sections may have a bow shaped end, while the other section has 55 a stern shaped end, as shown in Fig. 1, at 4 and 5, respectively. The sections 1 and 2

may also be of any desired size and dimensions as to length and width to accomodate the mechanism hereinafter described.

Mounted in bearings in a suitable frame 6 60 on one of the float sections is a rotary power shaft 7, having fast thereon a pair of oppositely arranged ratchet wheels 8 and 9, while midway between the ratchet wheels is a disk shaped guard wheel 10, which is also 65 fast on the shaft. Between the wheels 10 and the ratchet wheels 8 and 9 are arranged pinions 11 and 12, carrying dogs or pawls 13, preferably backed by springs 14 and engag- 70 ing the teeth of the ratchet wheels, as shown.

In connection with each of the pinions 11 and 12, I employ a rack, the two racks being designated 15 and 16, and under the preferred embodiment of the invention these two racks are connected together by end 75 cross bars 17 into the form of a frame of general rectangular shape as shown, the said racks being thus caused to travel in engagement with the pinions at all times. Leading off from the rack frame thus formed, is a 80 pitman or connecting rod 18, one end of which is pivotally connected to the rack frame while its opposite end is pivotally connected to a stanchion 19 on the other section of the float.

It will be seen that as the float sections rise and fall under the action of the waves, due to their pivotal relation to each other, the pitman will be actuated lengthwise and impart a corresponding movement to the 90 rack frame. This causes the racks 15 and 16 to actuate the pinions 11 and 12, first one and then the other, in the same direction, the pawls carried thereby acting upon the ratchet wheels in like manner, the result 95 being that the power shaft 7 is driven always in the same direction. The power thus transmitted to the power shaft may be taken off in any suitable way as by mounting a sprocket wheel 20 thereon, as shown in Fig. 100 4, and the power so developed and taken off may be delivered by suitable connections to any desired point for any needed purpose.

The mechanism above described may be duplicated, as shown in Fig. 1, for simultaneously driving two or more rotary shafts. In fact any desired number of sets of converting mechanisms may be utilized, according to the size of the float sections and other 105 conditions.

I claim:

1. A wave motor comprising a sectional

float the sections of which are pivoted to one another, and rack and pinion converting mechanism mounted on said sections and embodying a pinion member mounted on one section, and a pinion actuating rack connected with and actuated by the adjoining float section.

2. A wave motor comprising a sectional float the sections of which are pivoted to one another, and converting mechanism comprising a rotary member mounted on one

float section, a rigid stanchion on the adjoining section, a reciprocating member coöperating with the rotary member, and a connecting rod extending from said stanchion 15 to the reciprocating member.

In testimony whereof I affix my signature in presence of two witnesses.

WILLIAM E. HILLSON.
